PUMP.

Application filed January 3, 1924. Serial No. 684,242.

To all whom it may concern:

- Be it known that I, EUGENE J. HANSON, a subject of the King of England, residing at Edmonton, in the Province of Alberta 5 and the Dominion of Canada, have invented new and useful Improvements in Pumps, of which the following is a specification.
- My invention has reference, in its broad aspect, to improvements in pumps of the 10 type exemplified by a novel multiple action pumping head operable within a floating member constituting a compression chamber and a valve cut-off which is carried by the pump casing; and more particularly my invention 15 is designed to provide a pump having novel means for automatically preventing clogging and the like of the valves thereof irrespective of the type or purity of the substance pumped.
- 20 The concept embodied in my present invention includes, among other equally advantageous features which will be apparent as this description proceeds; first, means in the form of separate intakes for each of a plurality of displacement chambers whereby certain quantities of different substances to be pumped may be acted upon; the number of such substances being proportionate to the number of separate displacement chambers; second, to provide a pumping unit which may be associated with any reasonable number of separate displacement chambers; third, to attain such pumping action by means of the creation of a partial 25 vacuum, and thereby complete filling of the displacement chamber, or chambers, as well as complete emptying thereof during a working cycle; fourth, to provide a pump which will be equally effective when operating upon a variety of substances, whether pure or impure, and among which are oil, water, chemicals, gases or air, and the like, and one which may be utilized with either deep or shallow wells; fifth, to provide a 30 novel pumping head and floating member forming a displacement chamber and valve cut-off, each independently movable across a major intake port whereby to prevent clogging of such port, and; fifth, to attain 35 the foregoing and other ends through the medium of a simple and durable structure which may be cleaned with facility, set up or taken down with ease, and which will be inapt to become broken or deranged 40 through hard usage.
- 55 The particular elements of my pump em-

ployed to accomplish the objects attributed to it will be hereinafter more fully described in detail and specifically pointed out in the claims appended hereto and forming a 60 part of this specification.

In the accompanying drawing wherein is illustrated the preferred embodiment and a slight modification of my invention;

Figure 1, is a longitudinal sectional view 65 of the pump with its operating parts shown in the neutral position,

Figure 2, is a view similar to Figure 1, but with the operating parts shown at the completion of one half of a cycle of operation,

Figure 3, is an end view showing one type of bracket used with my pump,

Figure 4, is an end view showing another type of bracket,

Figure 5, is a perspective view of the type of bracket shown in Figure 3,

Figure 6, is a perspective view of the type of bracket shown in Figure 4,

Figure 7, is a slightly modified form of 80 my pump which is particularly adapted for deep well pumping, and,

Figure 8, is a type of connection which I use in adapting my pump for use as one of the ratio mixing type.

Like characters of reference designate like or similar parts throughout the several views of the drawing, in which;

The cylindrical pump casing (1) is formed with a cylindrical bore (2) extending longitudinally and eccentrically thereof. Mounted for reciprocation in the bore (2) of the casing are cooperating members (3) and (4); the member (3) constituting the pumping element, and the member (4) a floating displacement chamber and valve cut-off. The pumping element (3) is formed with a shank (5) having a flat side (6) and an arcuate side (7), and extending from the shank (5) is a stem (8) to 100 which is pivoted the operating lever (9) of a power unit (not shown). A link connection (10) which is pivotally engaged with the end of the lever (9) and with a bracket (11) on the end of the pump casing (1) affords the required leverage.

Formed on the shank (5) of the pumping element (3), and extending from the flat side thereof is a semi-cylindrical pumping head (12). The head (12) is also formed with a flat friction surface which is adapted to reciprocate upon the flat bear-

5 of the member (3) rides upon flat friction surfaces provided on the ends (14) of the member (4), consequently the assembly of the two members forms a cylindrical pumping unit which is freely reciprocable within 10 the bore (2) of the casing (1). Suitable compression rings (15) are carried by the ends of the member (4) for an obvious purpose, and packing glands may be utilized between the casing (1) and the unit comprising the members (3) and (4).

Formed in the casing (1) medially of its length is an inlet port (16) with which is adapted to register a corresponding port (17) in the web of the member (4); and in 20 the neutral position illustrated in Figure 1, both ports (16) and (17) are in registry and are closed by the pumping head (12) of the member (3). An inlet pipe (18) discharges through the port (16), and is provided with a flap valve conventionally illustrated and designated by (19), and designed to prevent return of the pumped substance under reduced suction.

In the neutral position shown in Figure 30 1, the pumping head (12) divides the space between the two ends (14) of the member (4) into two chambers hereinafter designated A and B. The member (4) is normally maintained in the neutral position by 35 opposed springs (20) which bear against the ends thereof. Springs (20) are carried by pins (21) which are slidably mounted in openings (22) in brackets (23) and (24), and such openings are countersunk as at 40 (25) to receive a portion of the normal length of each spring. Each bracket is also formed with a second opening (26) which is adapted to receive a bolt (27) for mounting the brackets on the ends of the 45 casing (1). The bracket (23) is formed with a body (28) provided with a grooved edge for receiving the discharge pipe (29) of the pump, and a laterally and angularly extending arm (30). The free end of the 50 arm is angularly cut down as at (31) so that when the bracket is mounted upon the end of the casing (1) in the manner shown in Figure 3 the flat side (6) of the shank of the member (3) will ride upon and be 55 supported thereby. The bracket (24) is formed with a body (32), and a lateral arm (33) which extends at right angles to the body and is adapted to support the opposite end of the shank (5) of the member (3). 60 It will be noted that the body (33) rises above the arm (32) thus affording a guide for the shank (5).

Formed in the casing (1) are outlet ports 65 (34) which are closed in the neutral position shown in Figure 1 by the ends of the

ports of the pump are closed, but as the member (3) is moved toward one end the substance to be pumped is compressed in the direction of movement and a suction is created behind the pumping head (12). In Figure 2 is shown the position of the elements of the pump at the completion of one half of a cycle of operation. To complete the partial cycle illustrated in Figure 2, the pumping head (12) has moved from the neutral position, thus compressing the pumped substance in the chamber A, and creating suction in chamber B. The compressed substance in the chamber A acts to move the member (4) against the resistance of that spring (20) located in the direction of movement, and as the movement of member (4) continues the ports (16) and (17) become disaligned and the supply cut off, while the end of the member (4) is moved to gradually open one of the outlet ports (34). Thus at the completion of one half cycle chamber A is completely emptied, and a high degree of suction is created in chamber B. Upon the return stroke the ports (16) and (17) come into registry and the substance to be pumped is drawn quickly and with great force from the pipe (18); the ports are then moved out of registry and compression in chamber B with proportionately increased suction in chamber A follows.

From the foregoing it is believed that the 95 operation of my pump will be apparent. The advantages of such a structure are manifold, but it is obvious that constant movement of the head (12) and port (17) with respect to the port (16), and of the ends 100 (14) with respect to ports (34) will absolutely prevent the accumulation of clogging matter irrespective of the impurities or of the inherent nature of the substance pumped. Furthermore, my pump is 105 exceedingly effective due to the complete displacement of substance, and the attainment 110 of an almost perfect vacuum through the absence of air pockets. It is also emphasized that these advantages are accomplished 115 without the use of fragile valves, and other parts liable to get out of order or broken.

A slightly modified form of my invention which is especially adapted for deep well pumping is illustrated in Figure 7. In this 120 form the member (3) is provided with a plurality of pumping heads (12), which operate in multiple chambers formed by the utilization of a plurality of members (14) on the member (4). In the present instance 125 there are two pumping units, each having associated therewith intake and exhaust ports such as have been described in connection with the principal embodiment. In my deep well pump, however, the intake 130

and exhaust pipes extend longitudinally of, and within, the walls of the casing (1) and outwardly from the respective ends thereof. It is also necessary to utilize but one spring 5 (20) as the weight of the moving parts is sufficient to accomplish the desired purpose. However, two springs may be used if found desirable—the other spring being shown in dotted lines. The pump casing is prefer- 10 ably mounted by a bell type fitting conventionally shown here in dotted lines also. The peculiar character of my pump makes it particularly adaptable for deep well pumping in that it is not only inapt to clog, 15 but its action is positive and the pumping operation completed with maximum efficiency, on both the upward and downward strokes.

In Figure 8 is shown a pipe connection 20 which I have found it expedient to utilize when it is desired to use my pump as one of the ratio mixing type. Several different kinds of substances may be pumped at the same time by utilizing the type of my pump 25 shown in Figure 7. This is accomplished by using multiple intakes—one for each chamber—and pumping a different substance into each chamber. Thus, by connecting my present fitting to the discharge 30 ports all such substances are correctly mixed, and proportions may be varied if desired by modification of the respective intakes or the chambers.

While in the foregoing there has been 35 illustrated and described such combination and arrangement of elements as constitute the preferred embodiments of my invention, it is nevertheless desired to emphasize the fact that interpretation of the invention 40 should only be conclusive when made in the light of the subjoined claims.

Having described my invention and its objects with such attention to detail as will thoroughly acquaint one skilled in the art 45 with its construction and advantages, I claim:—

1. A pump of the type described comprising relatively movable pumping members, a shank formed on one member, a web formed 50 on the other member, and relatively co-operating bodies carried by said members and slidably engaging said shank and web

respectively, a casing adapted to receive said members, and said bodies adapted to approach each other upon movement of said members in said casing for the purpose de- 55 fined.

2. A pump of the type described comprising relatively movable pumping members formed with offset bodies movable upon a 60 common center line of reciprocation, means for limiting the stroke of one of said members with respect to the other whereby to cause said bodies to approach each other at the end of a stroke, and a casing adapted to 65 receive said members for the purpose de- fined.

3. A pump of the type described comprising a casing formed with inlet and exhaust ports, a movable member carried within the 70 casing and formed with inlet and exhaust ports adapted to register with the inlet and exhaust ports in the casing, means formed on said member for dividing the interior of the casing into a plurality of compartments 75 each communicating with an inlet port and an exhaust port, a reciprocating member operable within the casing and upon the movable member for alternately creating compression and suction in the respective chambers, and spring means for limiting the movement of the movable member. 80

4. A pump of the type described comprising a cylindrical casing formed with inlet and exhaust ports, a reciprocable member constituting a displacement chamber carried within the casing and formed with inlet and exhaust ports adapted to register with the inlet and exhaust ports of the casing, heads 85 formed on said member for dividing the interior of the casing into a plurality of compartments, a second reciprocating member operable within the casing and upon the first member, a head formed on said second reciprocating member intermediate its extremities and operable between the heads of the first member for alternately creating compression and suction in the respective chambers, and spring means associated with the first member for limiting the movement 90 thereof. 95

In testimony whereof I affix my signature hereunto.

EUGENE J. HANSON.
